(57) **CLAIM**

The ornamental design for a light guide body for a light emitting diode lamp, as shown and described.

DESCRIPTION

FIG. 1 is a perspective view of a light guide body for a light emitting diode lamp showing our new design;

FIG. 2 is a front view thereof;

FIG. 3 is a top plan view thereof;

FIG. 4 is a left side view thereof; and,

FIG. 5 is an enlarged left side view thereof.

Since a rear view is symmetrical to the front view thereof, the rear view is omitted.

Since a bottom view is identical to the top plan view thereof, the bottom view is omitted.

Since a right side view is identical to the left side view thereof, the right side view is omitted.

The whole article is transparent.
